UNITED STATES PATENT OFFICE.

ARTHUR BATES, OF LEICESTER, ENGLAND, ASSIGNOR TO UNITED SHOE MACHINERY COMPANY, OF PATERSON, NEW JERSEY, A CORPORATION OF NEW JERSEY.

LASTING-MACHINE.

1,096,486.

Specification of Letters Patent. Patented May 12, 1914.

Original application filed June 18, 1910, Serial No. 567,663. Divided and this application filed May 23, 1912. Serial No. 699,202.

To all whom it may concern:

Be it known that I, ARTHUR BATES, a subject of the King of England, residing at Leicester, Leicestershire, England, have invented certain Improvements in Lasting-Machines, of which the following description, in connection with the accompanying drawings, is a specification, like reference characters on the drawings indicating like parts in the several figures.

This invention relates to lasting machines, and more particularly to certain improvements in lasting machines of the type disclosed in United States Letters Patent No. 584,744, dated June 15, 1897. In the machine of said Letters Patent the upper is worked into lasted position by devices acting upon successive portions of the stock by repeated operations, such devices comprising pincers which are actuated to grip and pull the upper, and to lay it over upon the innersole, and a wiper which follows the movements of the pincers and wipes or presses the overlaid upper material smoothly upon the sole. The upper is secured in lasted position by tacks one of which is deposited in an aperture in the wiper by suitable devices prior to each advance movement of the wiper over the shoe, and at the completion of such movement the tack is driven through the lasted portion of the upper by a suitable driver. Machines of the type referred to are also provided with mechanism to impart to the pincers lateral movements, and axial turning movements, to plait the upper at those portions of the shoe where excessive fullness of the stock calls for such operation, the said mechanism being under the operator's control through devices which enable him to vary the direction and extent of, as well as to initiate, or entirely suspend the plaiting movements at will.

A very important feature of the present invention consists in improved mechanism for wiping the upper into lasted position comprising a wiper which is so constructed and arranged for operation as to move in an inclined path relatively to the edge of the shoe.

In the herein described embodiment of the invention the wiper comprises two members that are arranged for simultaneous movement toward and from the shoe, in a direction which may be normal to a curved

edge of a shoe, along convergent paths that are inclined to the median line of the machine, so as to wipe the upper inwardly from the edge of the sole, and at the same time in opposite directions along or substantially parallel with said edge. The wiper members are preferably crossed, as shown, and are pivoted at an intermediate point to their carrier, and have their rear portions provided with guiding slots which are entered by a pin or projection rigid with the frame of the machine. When the carrier moves inwardly toward the shoe and advances the wiper members over the edge of the sole the movement of the pin or projection along the guiding slots causes the wipers to approach each other in the manner of a pair of shears, and when the carrier moves away from the shoe a separating movement of the wipers is effected by the same means.

Other features of the invention, including important details of construction and combinations of parts, will be hereinafter more particularly described and claimed.

This application is a division of my Patent No. 1,029,840, granted June 18, 1912, in which the generic claims are made covering broadly the construction herein illustrated.

In the drawings, Figure 1 is a perspective view of the principal operative parts of a lasting machine with an embodiment of the present invention applied thereto, the supporting pedestal and frame being omitted; Fig. 2 is an exploded view, showing in perspective the wiper and its actuating devices. Fig. 3 is a plan view of the wiper.

The main shaft 1 of the machine, which turns in suitable bearings in the frame, carries a cam block 2 which is provided with a cam groove or way to receive a roll on a slide 4 which is connected at its upper end to a rocking lever 5. This lever is fulcrumed at 6, and is connected at its forward end to the pincer bar 8, which is formed as a sleeve and carries at its lower end the jaw 10. The other pincer jaw 12 is connected to a rod 14 that extends upwardly through the sleeve 8 and is engaged at its upper end by a spring-pressed plunger 16 in a lever 18. The lever 18 is fulcrumed at 20 in the lever 5 and carries on its rear arm 21 a roll that rests upon an edge cam 22. The block having the edge cam 22 has also

a cam groove in its front face to receive a roll on a lever 25, which is fulcrumed on a rod 26 and at its outer end carries a segmental rack whose teeth engage a pinion 28 on a sleeve shaft 30. This shaft is connected to a rocker 32 which carries a block 34 connected by the rod 35 with a cross head 36 by means of which the pincers are caused to move or swing laterally. A link 37 connects the cross head 36 with a lever 39 which is fulcrumed through an adjustable block to a pin 41 supported from the frame of the machine. The upper end of the lever 39 is connected through a rod 43 with a rack which meshes with a pinion fast on the upper part of the pincer bar 8, whereby to effect the axial turning movements of the pincers simultaneously with the lateral movements of the pincers in forming the plaits or folds, said parts being fully shown and described in Letters Patent No. 584,744 heretofore referred to. The cross head 36 is supported in a yoke 38 on the front end of a slide rod 40 which carries a roll that is engaged by the rear face of the cam 22. A spring 42, acting through a lever 44, holds the rod forward with the roll against the cam. A vertically reciprocating rod 50 which is guided in a boss on a bracket supported from the frame of the machine is pivotally connected at one end with an arm of a bell-crank lever 46, said rod having the usual operating mechanism including a knee lever as shown. The bell-crank lever 46 is fulcrumed at 60 to the main frame, and is shown as having one arm formed as a yoke 62 which embraces a collar 64 connected through an inclined slot and pin, or the like, with a shaft 55 located within the sleeve shaft 30. The connection between the collar and the shaft 55 is such that a movement of the collar endwise on the sleeve serves to turn the shaft through a small angle. The shaft 55 is connected at its front end with the block 34 through a rack and pinion, or the equivalent, whereby when the shaft is rotated in either direction, by sliding the collar 64 along the sleeve 30, the block will be adjusted in the rocker 32 from 50 and toward the center of the rocker, and to either side thereof, for starting and stopping the lateral and turning movements of the pincers, and for controlling the direction and extent of such movements.

55 The mechanism described above for lowering and raising the pincers, closing them, and swinging forwardly and backwardly, and for effecting their plaiting movements are fully described in the aforesaid Letters 60 Patent No. 584,744, and of themselves form no part of the present invention. In the operation of these parts it is deemed sufficient to explain that the pincers with the jaws open are lowered by the cam 2 into 65 position to seize the upper, closed by the

cam 22, then uplifted by a further movement of the cam 2, and then moved forwardly over the shoe bottom by the spring 42. When the knee lever is set to adjust the block 34 in an eccentric position in the 70 rocker 32 the pincers receive also lateral and twisting movements for plaiting the upper, the plaits being laid inclined in either direction from the median line of the shoe at the toe, or at the heel, according 75 to the position into which the block 34 is moved by the knee lever. A rocking lever 66 is fulcrumed at 68 to a bracket projecting from a rigid part of the frame 3. The upper end of the lever 66 carries a roll which operates in a cam groove formed in a cam block 70, which is fast on the driving shaft 1. The lower end of the lever 66 is connected with a slide bar 72 which is suitably guided for horizontal movement in the 80 machine frame and at its forward end carries a wiper to coöperate with the pincers in working the upper into lasted position. In prior machines of this type, similar parts to those just described are shown, the wiper 85 being rigidly carried at the forward end of the slide bar, and being provided with an aperture to receive a tack.

In operation, the slide bar is reciprocated to carry the wiper back and forth by the cam 70, and when it reaches a suitable position in its rearward movement a tack is deposited from a raceway by suitable devices in the aperture of the wiper, the wiper is then carried forward in proper time relation 95 to the operation of the pincers, wipes the overlaid upper onto the innersole, and a driver forces the tack carried by the wiper through said parts of the shoe to secure them together. According to the present invention the wiper is not fixed to the slide bar 72, by which it is operated in previous machines of this type in a straight line toward and from the edge of the shoe, but is movably supported by the bar and operated in such 100 manner that it has other movements imparted to it, whereby it may wipe or press the upper in directions which will conform to the inclination of the folds or plaits in the upper at the toe or at the heel of the shoe, as 115 will be now more particularly described. The reciprocating slide bar 72 has secured to its forward end by screws 76 a wiper carrier or support 74 Fig. 2. The carrier 74 is shown as having a tack-receiving aperture 120 78, and at a suitable point preferably to the rear of its forward extremity is apertured to receive a stud or screw 80 from which the parts of the wiper are pivotally supported at a point between their ends. The wiper members are shown as having notches in their inner edges which form a tack-receiving aperture 84 which is so located as to register with the aperture 78 in the carrier 74 when the wiper members occupy their central or 130

closed position, and is therefore in longitudinal alinement with the carrier.

As herein shown the wiper comprises two independent, movable sections, which are so constructed and arranged for operation that when they occupy a retracted position said sections are extended laterally from the center line of the wiper-carrying slide bar, or actuator, and have their acting edges and faces inclined relatively to said line, but as said sections are advanced toward the shoe they are caused to approach each other and wipe the stock laterally along convergent paths that meet at said center line. In this construction, the wiper sections comprise the two bars 116 and 117, which are crossed similar to a pair of shears, and supported by the single pivot 80 which may be sustained from a carrier such as that indicated by the numeral 74, in Fig. 2, to be reciprocated horizontally by the slide bar, or by any suitable member having movement to carry the wipers toward and from the shoe. To the rear of the pivotal connection 80 the wiper bars are provided with slots 120, which receive a pin or roll 122 which is fixed rigidly to a part of the machine frame. When the slide bar is advanced in the operation of the machine the slots 120 will slide over the pin or roll 122 and cause the wiper sections to close together as they are advanced, the construction, as well as the operation of these parts, corresponding somewhat to those of a pair of shears. The carrier or support for the wiper sections may be adjustably secured to the slide bar, and in that case the pin or roll 122 will be adjustably fastened to the stationary part of the frame which supports it.

While the parts of the wiper are deflected outwardly from the longitudinal central line of the machine when retracted, it is necessary that at its most advanced position the wiper should present its tack-receiving aperture in alinement with the aperture 78 in the carrier and also in alinement with the driver 79 in order that the tack may then be driven into the stock. To this end the slots 120 are inclined relatively to the center line of the machine and extend inwardly and toward the rear. The inclination of these slots to each other will therefore be greatest when the wiper is in its extreme rear position, and as the two-part wiper advances toward the shoe the lateral deflection or inclination of its parts will decrease gradually as the roll 122 approaches the outer end of the slots 120. Said roll being in line with the central line of the machine, the wiper will, as a whole, occupy a central position where its aperture 84 is in alinement with the aperture 78 and also with the driver 79.

It is thought that the operation of the several features above described, as well as their advantages, will be apparent without further

description. The wiper, as in former machines of this same general character, is so actuated in time relation to the operation of the pincers that when the pincers have seized the upper, uplifted to stretch the leather, and moved inwardly to lay the upper upon the innersole, the wiper is advanced and wipes smoothly the overlaid stock into its final lasted position and in accordance with this invention the wiping movements take place along convergent paths directed toward the driver which descends and forces into the stock the tack which was carried forward by the wiper. It is to be understood, however, that while the herein described wiper is useful in the operation of forming plaits or folds in connection with pincers whose movements are such as those described herein, the invention is not in any sense limited to the use of such wiper with pincer mechanism that produces plaiting movements, nor in fact with any pincer member, for it will be obvious to those skilled in the art that wipers having such capacities for movement will have many advantages in lasting machines that work the upper into lasted position without the use of pincers.

Having described my invention, what I claim as new and desire to secure by Letters Patent of the United States is:—

1. A machine of the class described having, in combination, a wiper having two members arranged for movement along convergent paths to wipe an upper into lasted position, continuously operating actuating mechanism for said wiper for working into lasted position successive portions of the upper by repeated operations, and means for progressively securing the overworked upper in lasted position.

2. A machine of the class described having, in combination, a wiper, comprising two members arranged for movement in oppositely inclined directions to wipe an upper along convergent paths toward a tack receiving point, continuously operating actuating mechanism for the wiper to enable it to operate successively on adjacent portions of the upper, and means operating automatically in time relation to the wiper movements for tacking the upper in lasted position.

3. In a lasting machine, a wiper comprising two crossed members pivotally connected at an intermediate point, said members having slots in their rear portions, a pin supported from a stationary part of the machine and arranged in said slots, and means to move said members toward and from a shoe, said parts being so arranged and constructed that the forward ends of the wiper members will approach each other during their forward movement and will separate during their rearward movement.

4. A machine of the class described hav-

4
ing, in combination, pincers, mechanism for giving the pincers overdrawn movements, a two-part wiper the members of which are arranged for movement obliquely from opposite lateral sides of the path of the overdraw pull of the pincers toward said path, and actuating means for operating the wiper continuously in time relation to the pincer movements to work successive portions of the upper into lasted position by repeated operations carried on progressively about the shoe.

5 5. A machine of the class described having, in combination, pincers, mechanism for giving the pincers updraw and overdraw movements, wipers arranged for movement inwardly and obliquely toward the center line of the pincers from opposite sides of said line to work the upper into lasted position, means for actuating the wipers continuously in time relation to the pincers to work into lasted position successive portions of the upper, and means for securing said portions in position progressively.

10 6. In a machine for lasting an upper progressively step-by-step, the combination of a reciprocating carrier, tacking devices thereon, and means operating in time relation to the carrier for working in the upper over the toe or the heel end of the last upon each side of the tacking point in directions approximately radial to the curve of the last end.

15 7. A machine of the class described, having in combination, tacking devices, means for reciprocating the tacking devices over the shoe bottom, and means arranged for actuation upon the tacking devices for working in the upstanding margin of the upper material obliquely over the last edge from opposite sides simultaneously toward the tacking point.

20 8. A machine of the class described, having, in combination, pincers for pulling an upper over a last, a wiper comprising members arranged to engage the upper at the rear of the pincers upon each side of the portion that is being directly pulled, means for actuating the wiper members to press the portion of upper that is being tensioned inwardly and laterally from opposite sides, and means for operating said pincers and wiper in time relation for working into lasted position successive portions of the shoe upper progressively about the shoe.

25 9. A lasting machine having, in combination with suitable actuating means, a wiper comprising two members which are advanced over the shoe bottom by said actuating mechanism to do their work and are caused by said mechanism to assume an open shear-like relation to one another when they are

retracted and to assume a fully closed shear-like relation by the time their advance is completed.

65

10 10. A step-by-step lasting machine arranged to permit a shoe to be advanced relatively thereto for presentation of adjacent portions successively to the action of said machine for progressive lasting, said machine having continuously running actuating mechanism and wiper members connected therewith and advanced thereby over the shoe bottom in paths which converge, said wiper members being also turned toward each other by said mechanism as they are advanced.

70

15 11. A step-by-step lasting machine arranged to permit a shoe to be advanced relatively thereto for presentation of adjacent portions successively to the action of said machine for progressive lasting, said machine having continuously running actuating mechanism and wiper members which are advanced over the shoe bottom by said mechanism and turned relatively to one another from an open, diverging relation when they start to a closed substantially parallel relation when their advance is completed.

75

20 12. A step-by-step type of lasting machine having, in combination, a wiper, a continuously running carrier to reciprocate the wiper bodily toward and from the shoe, said wiper comprising two members, and means to cause the members to swing from opposite directions toward the median vertical plane of the machine as they are advanced and reversely as they are retracted.

80

25 13. A step-by-step type of lasting machine having, in combination, a reciprocating carrier, a wiper comprising two members each movably supported by the carrier, and means to cause each wiper member to assume an inclined relation to the carrier on its rearward movement and to aline each member substantially with said carrier on its forward movement.

85

30 14. A step-by-step type of lasting machine having, in combination, a reciprocating carrier, a wiper comprising two members each movably supported by the carrier, and means arranged for adjustment to cause the two wiper members to approach the shoe in substantially the line of movement of said carrier or in directions oppositely inclined, respectively, to said line.

90

35 In testimony whereof I have signed my name to this specification in the presence of two subscribing witnesses.
